JOSEPH SUDEK, JR., OF EAST PATERSON, NEW JERSEY

HAWK

Application filed November 2, 1927. Serial No. 230,479.

This invention relates to what are known as hawks, and particularly to devices of this class used by masons in plastering and other masonry; and the object of the invention is 5 to provide a hawk of the class specified, which by reason of its construction may be knocked down to form a comparatively small package, and to materially reduce the dimensions of the tool; a further object being to provide 10 a tool of the class specified, which is composed of a plurality of sheet metal parts with means for quickly coupling and uncoupling said parts; a further object being to provide one of the parts of the tool with handle member 15 retained against displacement from said part but movable relatively thereto in securing the separate parts of the tool together and in compactly folding said parts for shipment or packing in a tool kit or other container; 20 a further object being to provide means involving part of the handle construction for securing and retaining the separate parts of the tool together in an operative position; and with these and other objects in view, the 25 invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in 35 each of the views, and in which:

Fig. 1 is a perspective view of a tool made according to my invention.

Fig. 2 is a section on the line 2—2 of Fig. 1.

Fig. 3 is a partial section on the line 3—3 40 of Fig. 1.

Fig. 4 is a plan view of one part of the tool.

Fig. 5 is a view similar to Fig. 2 and showing a modification; and,

Fig. 6 is a detail view of a part of the construction shown in Fig. 5.

In carrying my invention into effect, I construct the main body portion of my improved hawk from two similar plate members 10 and 11, both of which are oblong in 50 form and are provided on their adjacent

edges, when placed together side by side, substantially centrally of the adjacent side walls with rectangular recesses 12 and 13, formed by pressing the metal of the plates 10 and 11 downwardly. The bottom walls of the recesses 12 and 13 are provided with apertures 14 and 15 to receive the flanged ends 16 of a lock and coupling bar 17 which serves to couple the plates 10 and 11 together.

The bar 17 carries centrally thereof a downwardly directed pin 18, which passes through an aperture 19 formed between the plates 10 and 11 in the recess portions thereof. Pivoted to the pin 18 is the yoke end 20 of a rod 21 having spaced threaded portions 22 and 23 forming on said rod, between said threaded portions, a blank or non-threaded portion 24, for the purpose later described.

It will be noted that the bar 17 fits snugly in the recesses 12 and 13 and with the upper face of said bar flush with the corresponding face of the plates 10 and 11, thus presenting a smooth and unobstructed top face to the body of the hawk, riveted, welded or otherwise secured to the lower face of the plates 10 and 11 adjacent the side edges 25 and 26, and also adjacent the abutting side edges of each of said plates are flange strips 27 into which the side edges of a mounting and reinforcing plate 28 are adapted to be placed. The mounting plate 28 is arranged longitudinally of the abutting edges of the plates 10 and 11 and extends equidistance onto the lower face of said plates and is provided centrally with a depressed portion 29 to receive the depressions on the plates 10 and 11 formed by the recesses 12 and 13.

Said depressed portion 29 is provided centrally with an aperture 30 through which the pin 18 is free to pass as well as the rod 21. With this construction, it will be apparent that the plates 10 and 11 are retained against lateral displacement on the mounting plate 28 by reason of the flange strips 27 employed.

The parts are retained in coupled position by means of a handle member 31 having a bore 32 extending centrally therethrough, and in which is fixed a threaded collar or sleeve 33 held in the desired position of adjustment by a set screw 34. The threaded

portions 22 and 23 of the rod 21 are in threaded engagement with the sleeve 33. By means of this construction, the handle member 31 or the upper face thereof may be brought into firm engagement with the lower face of the mounting plate 28 or the depression 29 thereof. Likewise, the lock and coupling bar 17 will be drawn into the recesses 12 and 13 with the flanges 16 of said bar entering the apertures 14 and 15, and the parts will thus be firmly coupled together. In this position, the threaded portion 22 of the rod 21 is in engagement with the collar 33.

To dissect the parts, the handle member 31 is rotated on the rod 21, or said handle member may be held in the hand with the plates 10 and 11 directed downwardly, and said plates as a unit spun around or with reference to the fixed handle member until the threaded portion 22 disengages the threaded sleeve 33, at which time, the body of the tool together with the bar 17, pin 18 and rod 21 will drop with reference to the handle member by virtue of the unthreaded or blank portion 24 on said rod until the threaded portion 23 engages the sleeve 33. In this position, the yoke end 20 of the rod 21 extends beyond the upper end of the handle member 21, and permits the handle member to be swung into position at right angles to the pin 18 as indicated in dotted lines in Fig. 2 or into a position in parallel relation to the mounting plate 28. It will also be understood that the lock bar 17 may be disengaged from the recesses 12 and 13, and the plates 10 and 11 dissected from the mounting plate 28 to permit of the compact packing of the complete tool.

It will be understood that the non-threaded portion 24 provides for a quick coupling and uncoupling of the parts and the threaded portion 23 operates to prevent dissection or uncoupling of the handle member and lock bar with reference to the mounting plate, but if it should be desired to do so, the handle member member may be detached from the rod 21 by rotating the same thereon until the threaded portion 23 is free from the collar 33.

In Figs. 5 and 6 of the drawing, I have shown a slight modification, wherein the plates 10 and 11 are directly coupled with the mounting plate 28 by providing the plate 28 at spaced intervals and adjacent the corner portions thereof with key hole apertures 35 to receive headed rivets 36 on the plates 10 and 11, and arranged in such position that the heads of the rivets will pass through the large portions 37 of the apertures 35 and the shanks will enter the smaller portions 38 of said apertures, and when in the latter positions, the plates 10 and 11 will be in proper alinement.

With this construction, it will be apparent that the movement of the plates 10 and 11 longitudinally of the mounting plate 28 is essential, and accordingly, the depression 29^a of the mounting plate 28 is made larger to

permit the movement of the depressions 39 on the plates 10 and 11 within the depression 29. The recesses 40 formed by the depressions 39 on the adjacent edge faces of the plates 10 and 11 are not provided with the apertures 14 and 15, and the lock bar 17^a is not provided with the flanges 16. Otherwise, the bar 17 and the parts coupled therewith are identical to the structure shown in Figs. 1 to 4 inclusive. In other words, with the construction shown in Figs. 5 and 6, the rivets 36 in themselves are sufficient to key the plates 10 and 11 to the mounting plate 28, and the lock bar 17^a will clamp the parts together in this position, and also act as a key for properly alining the parts and retaining the outer faces thereof in flush relation.

It will be understood that the parts of the tool shown in Figs. 5 and 6 are detachable in the same manner as with the tool shown in Figs. 1 to 4 inclusive. While I have shown certain details of construction for carrying my invention into effect, it will be understood that I am not necessarily limited to these details and various changes therein and modifications thereof may be made within the scope of the appended claims, without departing from the spirit of my invention or sacrificing its advantages.

Having fully described my invention, what I claim as new and desire to secure by Letters Patent, is:—

1. A tool of the class described comprising a mounting plate, a handle member on said plate, and a body portion consisting of a plurality of detachably coupled plates adapted to be mounted on said mounting plate in an edge to edge relation, said mounting plate extending longitudinally of and supporting the adjacent edges of said plates to form when said plates are coupled together, a large body portion having a flush outer face.

2. A tool of the class described comprising a mounting plate, a handle member on said plate, and a body portion consisting of a plurality of detachably coupled plates adapted to be mounted on said mounting plate in an edge to edge relation, said mounting plate extending longitudinally of and supporting the adjacent edges of said plates to form when said plates are coupled together, a large body portion having a flush outer face, and means for retaining said plates against displacement from said mounting plate.

3. A tool of the class described comprising a mounting plate, a handle member on said plate, and a body portion consisting of a plurality of plates adapted to be mounted on said mounting plate in an edge to edge relation to form when said plates are coupled together, a large body portion having a flush outer face, means for retaining said plates against displacement from said mounting plate, and said last named means including said handle member, and means whereby said

handle member may be moved into a position parallel to the longitudinal plane of said mounting plate.

4. A tool of the class described consisting of two plate members of similar contour and provided on adjacent edge portions with recesses, a mounting plate extending longitudinally of the adjacent edge portions of said plates and having a recess into which the 5 depressions on said first named plates are adapted to rest, and other cooperating means 10 on said mounting plate and first named plates for retaining the first named plates in proper alignment one with reference to the other, and 15 means for securing said plates together to form the body portion of the tool.

5. A tool of the class described consisting of two plate members of similar contour and provided on adjacent edge portions with recesses, a mounting plate extending longitudinally of the adjacent edge portions of said plates and having a recess into which the 20 depressions on said first named plates are adapted to rest and other cooperating means 25 on said mounting plate and first named plates for retaining the first named plates in proper alignment, one with reference to the other, means for securing said plates together to 30 form the body portion of the tool, said last 35 named means involving a handle member arranged on one side face of the body portion, and a lock bar movable relatively to the handle member and arranged on the other side face of said body portion.

35 6. A hawk, the body portion of which is composed of two similar, elongated and rectangular plate members adapted to be coupled together in edge to edge relation to form said hawk body, means comprising a mounting 40 plate extending longitudinally of the abutting edges of said members and a handle member for detachably coupling said members, said handle member comprising a tubular body, a rod mounted in and in threaded 45 engagement with said body, the outer end portion of said rod having an extension pivoted thereto and provided with a head cooperating with said members, and said rod having a non-threaded inner shank portion permitting 50 of longitudinal movement of said tubular body thereon to permit the movement of said handle member on said pivot into a position parallel to the longitudinal plane of the hawk 55 body.

55 7. A hawk, the body portion of which is composed of two similar, elongated and rectangular plate members adapted to be coupled together in edge to edge relation to form said hawk body, means comprising a mounting 60 plate extending longitudinally of the abutting edges of said members and a handle member for detachably coupling said members, said handle member comprising a tubular body, a rod mounted in and in threaded 65 engagement with said body, the outer end por-

tion of said rod having an extension pivoted thereto and provided with a head cooperating with said members, and said rod having a non-threaded inner shank portion permitting of longitudinal movement of said tubular body thereon to permit the movement of said handle member on said pivot into a position parallel to the longitudinal plane of the hawk body and the inner end of said rod having a head limiting the movement of the tubular body of the handle on said rod.

8. A hawk, the body portion of which is composed of two similar, elongated and rectangular plate members adapted to be coupled together in edge to edge relation to form said hawk body, means comprising a mounting plate extending longitudinally of the abutting edges of said members and a handle member for detachably coupling said members, said handle member comprising a tubular body, a rod mounted in and in threaded engagement with said body, the outer end portion of said rod having an extension pivoted thereto and provided with a head cooperating with said members, said rod having a non-threaded inner shank portion permitting of longitudinal movement of said tubular body thereon to permit the movement of said handle member on said pivot into a position parallel to the longitudinal plane of the hawk body, and the inner end of said rod having a head limiting the movement of the tubular body of the handle on said rod, and said last 70 75 named head being threaded to permit of the attachment and detachment of the tubular body with respect to the rod.

In testimony that I claim the foregoing as my invention I have signed my name this 1st day of August, 1927.
